UNITED STATES PATENT OFFICE.

CHARLES BLAGBURN, OF SAN FRANCISCO, CALIFORNIA.

MINING APPARATUS.

SPECIFICATION forming part of Letters Patent No. 550,244, dated November 26, 1895.

Application filed December 31, 1894. Serial No. 533,385. (No model.)

To all whom it may concern:

Be it known that I, CHARLES BLAGBURN, a subject of the Queen of Great Britain, residing at San Francisco, in the county of San Francisco and State of California, have invented certain new and useful Improvements in Mining Apparatus; and I do hereby declare that the following is a full, clear, and exact description thereof.

10 My invention relates to an improved apparatus for raising or forcing water, gravel, sand, or other material under pressure and is more especially designed for use in mining operations for elevating inaccessible auriferous material to a position in which it can be treated for the extraction of gold.

In mining operations at the present day, and especially in gravel-mining, where water-elevators are employed to raise the material, 20 the most difficult problem to solve is that of obtaining a sufficient water-supply at a sufficient pressure and at reasonable cost. Many mines would be productive and yield large returns were it not for the disproportionate expense of working them, and one of the 25 principal items in the expense-account is the great cost of water. Water is now furnished to miners by companies organized for that purpose at rates which are always high and sometimes prohibitive. This water is obtained usually from supplies in the mountains and is delivered at lower elevations by flumes to different localities where it is used, reaching the mine at high pressure, although 30 in comparatively small volume. The supply of water being limited by its high cost, work in such mines progresses slowly on account of the limited capacity of the water-elevators now used, which have an excessive water-pressure but an inadequate volume to raise the material in sufficient quantity, and the valuable results of the mining operations are very small relatively to their cost.

The object of my invention is to take advantage of such a limited supply of water at high pressure by utilizing it not for mining operations directly, but for inducing an ample supply of water at a lower but still sufficient pressure from some other source. I am 45 thus enabled to supply water in sufficient quantities to greatly increase the amount of work performed without adding to the ex-

pense now incurred for performing a very much smaller amount.

A clear comprehension of my invention and 55 means for carrying it out will be obtained from the following description, which should be read in connection with the accompanying drawings, in which—

Figure 1 is partly an elevation and partly 60 a section representing the use of my invention in connection with a so-called "bar" of auriferous gravel. Fig. 2 is a longitudinal section of the pipes shown in Fig. 1.

In the drawings is represented the profile 65 of a cañon or ravine supposed to have a stream at the bottom. In Fig. 1 the auriferous bar or deposit is assumed to be in or near the bed of the stream and the point to which water and gravel are to be raised and where 70 the latter is to be washed is above the wall of the cañon.

A represents a sump or sink in the river-bed, formed of two chambers or compartments 75 A' and A², separated by a partition C and built of timbers suitably braced so as to form a rigid structure. The chamber A' has an open bottom to admit the water from the river. The chamber A² is closed at the bottom and forms the receptacle for the auriferous gravel dumped or shoveled into it.

B represents the supply-pipe, through which the stream of water from the flume is delivered at high pressure. This pipe extends down into the chamber A' and through an 85 opening in the end of the discharge-pipe D, which, as a whole, extends through the chamber A² and up the sides of the cañon, where it enters a flume E, leading to the point where the gravel is to be washed. The pipe D is 90 provided with a branch D', extending below the water-line in the sump, and the end of which is open to permit the water to enter freely. The pipe D is composed of several sections proportioned in number to its length. 95

In advance of the discharge end of the pipe B the pipe D is contracted, as at d, and is then expanded to form a ball for a swiveled nozzle-pipe D². This nozzle in turn enters the sectional pipe D³, forming a continuation 100 of pipe D and extending up the side of the cañon. The first section of pipe D³ is made tapering, so as to form a contracted portion d', above which the diameter may be uniform

throughout its remaining length. The nozzle is partly surrounded by a half-section of pipe d^2 , which provides an inlet-opening d^3 for the contents of the chamber A^2 . The branch D' 5 in the sump is preferably inclosed by a box F to prevent sand and sediment from being drawn into the pipe D .

In the operation of these hydraulic connections the stream of water from the distant 10 supply, passing at a high pressure through the pipe B , is injected into the discharge-pipe of greater diameter. The vacuum produced by the force of the jet induces a flow of water from the sump through the branch D' , 15 which mingles with the high-pressure stream, producing a combined flow of much greater volume, although of lower pressure. The pressure, however, is still amply sufficient in the nozzle-pipe to draw the gravel from the 20 chamber A^2 through the opening d^3 , and also to force the water and gravel together up through the pipe D^3 to the proper point above the cañon. With the greatly increased supply of water a correspondingly greater quantity 25 of gravel can be elevated and worked in a given time, and so, at the same expenditure for water as is now required, the amount of material and water supplied can be increased up to the extreme inductive limit of 30 the high-pressure stream.

It is evident, without special illustration, that the method above described can be used

in hydraulic mining with the ordinary monitor or giant. Indeed, the apparatus shown in Figs. 1 and 2 (supposing the piping above 35 the nozzle D^2 removed) can be operated as a hydraulic monitor, sufficient pressure being afforded by the water from the distant source, and the volume required for hydraulic mining being induced from the adjacent source 40 in the same way, as before described.

What I claim is—

1. The combination of a hydraulic gravel elevator with a water lifter for increasing the volume of water for ejecting or lifting such 45 gravel or similar material, substantially as described.

2. An apparatus for raising gravel or other similar material, consisting of a compound hydraulic elevator having an injecting nozzle 50 with a suction branch leading to a separate water supply, and having a second nozzle leading into a chamber having an opening to receive gravel or similar material, and a pipe connected to said chamber, through which 55 said gravel is elevated, substantially as described.

In testimony whereof I have affixed my signature, in presence of two witnesses, this 18th day of December, 1894.

CHARLES BLAGBURN.
